US00D698762S

(12) **United States Design Patent**
Zheng et al.

(10) **Patent No.:** **US D698,762 S**
(45) **Date of Patent:** **** Feb. 4, 2014**

(54) **EARPHONE**

(71) Applicant: **Sony Corporation**, Tokyo (JP)

(72) Inventors: **Qi Zheng**, Tokyo (JP); **Tomotsugu Minamikawa**, Tokyo (JP)

(73) Assignee: **Sony Corporation**, Tokyo (JP)

(**) Term: **14 Years**

(21) Appl. No.: **29/454,685**

(22) Filed: **May 13, 2013**

Related U.S. Application Data

(63) Continuation of application No. 29/421,744, filed on Sep. 13, 2012, now Pat. No. Des. 682,257, which is a continuation of application No. 29/371,938, filed on Feb. 1, 2012, now Pat. No. Des. 669,057.

CLAIM

(57) The ornamental design for an earphone, as shown and described.

DESCRIPTION

FIG. 1 is a perspective view of an earphone showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The portions indicated in broken lines are for illustrative purposes only and form no part of the claimed design. Dot-dash broken lines define the boundaries of, but are not included in, the claimed design.

1 Claim, 5 Drawing Sheets
